UNITED STATES PATENT OFFICE.

SHERWOOD C. BLISS, OF KENMORE, NEW YORK.

RAMMING MACHINE.

Application filed September 8, 1927. Serial No. 218,216.

My invention relates to a ramming or tamping machine for use in molding operations, which operates to ram or tamp molding sand or other material in a mold or flask 5 of a mold, so that a true impression of the pattern being used will be produced in the mold material. This ramming operation is preparatory to the assembling of the mold so that molten metal or other material may be 10 poured into the mold to produce a product of the desired material which will conform in shape to the pattern being used.

An important object of my invention is to provide an efficient ramming device so guided 15 and supported for travel across the mold that no part of the device or its supports will be in a position vertically above the mold or pattern at the time that the ramming device is in an inoperative position when the flask is 20 being placed over the pattern or sand is being placed on the pattern or into the flask. This construction avoids interference with sand chutes or measuring devices used for introducing sand or other material into the 25 mold or its flask. It also permits the location of the sand or mold material hopper directly above the mold and makes it unnecessary to employ moving buckets or chutes which are required where parts of the rammer supporting elements are at all times vertically above the mold or its flask. 30

Another object is to provide a ramming device having the elements for propelling and guiding it in its travel across the mold 35 so arranged that the relative movement of the contacting surfaces where friction occurs will be reduced to a small amount thus reducing the force required for propelling the device across the mold.

Another object is to arrange the guiding and propelling elements of the ramming mechanism so that the contacting surfaces where relative movement occurs may be adequately protected from the admission of grit 40 such as molding sand.

Another object is to provide a ramming device which will travel across the mold and will require a minimum of clearance or headroom directly over the mold, this making it 45 possible to locate the sand or material hopper a short distance above the mold so that the drop of sand or material from the hopper into the mold will not pack the sand or material excessively in the mold.

Another object is to provide a ramming 55 device which will travel across the mold and will require but one support extending to the floor and in this way reduce obstructions to the molding space and facilitate the erection and installation of the device. 60

Another object is to provide simplified means for preventing displacement of the sand or molding material by the rammer feet, in the direction of the travel of the ramming device relative to the mold. 65

Another object is to provide a device for removing the excess rammed or tamped sand or material from the top surface of the mold.

In the accompanying drawings:—

Figure 1 is a top plan view of my ramming device showing different positions of the device in full and dotted lines. The upper heavy dotted position is the inoperative position, the lower light dotted position is the position after the device has completed about half of its forward travel across the mold, the full lines show the position of the device at the end of its forward movement when it reverses its direction of travel and starts on its backward travel across the mold. 80

Figure 2 is an end elevation of the same.

Figure 3 is a partial vertical transverse sectional view of the upper part of the ramming mechanism, being taken on line 3—3, Fig. 1.

Figure 4 is a side elevation of the ramming machine, the position of its parts being in accordance with the position shown by full lines in plan Fig. 1.

Figure 5 is a partial vertical longitudinal section of the ramming mechanism, being taken on line 5—5 Fig. 2.

Figure 6 is a partial vertical transverse section of the rammer foot, being taken on line 6—6 Fig. 5.

Figure 7 is a partial vertical longitudinal sectional view of the means for allowing the rammer foot to maintain its position relative longitudinally to the mold while the foot is in contact with the sand or other material of the mold and the ramming device is moving longitudinally across the mold. 100

Figure 8 is a diagram of the movement of the parts of the rammer during the first part of the forward travel of the rammer and before the rammer foot has come into a position over the mold so that the foot contacts with the material of the mold. That is 105

when the controlling means shown in Fig. 7 are in a central position.

Similar reference numerals indicate like parts in each of the figures.

Pattern 11^b which may be a cope or drag half pattern is fast to pattern plate 11^a which in turn is fast to and supported by a table 11. The flask 10 is placed on the pattern plate 11^a and located in the proper relation 10 to the pattern 11^b by a lug and pin connection 12. Sand or other suitable material is placed in the flask or frame 10.

The ramming mechanism is supported by 15 and its movement in its travel across the mold is controlled and guided by two systems of arms or links; one system of arms and links being arranged in the form of a pantograph and supporting and guiding the ramming mechanism so that it will travel 20 horizontally along the desired path and the other system of arms and links being arranged in the form of a parallel motion linkage for maintaining the desired angular relation between the ramming mechanism and the path 25 along which it is constrained to travel by the pantograph linkage.

The accompanying drawings show the ramming mechanism guiding and supporting arms and links arranged so that the rammer will travel along a straight line and at the same time maintain a constant angular relation to the line of its travel.

A vertical fixed pivot pin 14 is the fixed 30 pivot for the pantograph which supports and guides the rammer mechanism. The pin 14 is fixed on the top surface of a standard or pedestal 13 which is located at one side of the table 11. A horizontally swinging arm 15 is pivoted intermediate its ends on 35 a pin 14 and at the outer end of its longer arm 16 carries a vertical fixed pivot pin 29.

A horizontally swinging arm 30 is pivoted intermediate its ends on pin 29 and at the outer end of its longer arm 31 carries a 40 vertical fixed pivot pin 33. A bracket 34 carries the ramming mechanism and is pivotally mounted on the pin 33. The shorter arm 17 of the arm 15 is bifurcated at its outer end to clear the rod 19 and each bifurcation carries a vertically fixed pivot pin 45 27^a. Links 28 are pivoted at one end on each pin 27^a and at their opposite ends on pins 27 which are fixed vertically in a trunnion collar 26. One of the pins 27 is on the 50 upper side of the collar 26 and the other pin 27 on the lower side of the collar 26. The shorter arm 32 of the arm 30 carries at its outer end a fixed vertical pivot pin 27^c. This pin 27^c is connected to the upper pin 27 by a 55 link 35. The arms 15 and 30 and the links 28 and 35 and their pivot pins form a pantograph in which the path of movement of the pins 27 is reproduced on an enlarged scale 60 by the path of the movement of the pin 33.

65 In the mechanism shown the ratio of the

movement of the pin 33 to the movement of the pins 27 is three to one. This is accomplished by making the ratio of the length of the arm 16 to the arm 17 and also of the arm 31 to the arm 32 three to one. The length of the link 28 is made equal to the length of the arm 32 and the length of the link 35 is made equal to the distance between the pins 27^a and 29 in the straight arm 15.

70 The trunnion collar 26 carrying pins 27 is fast to the rod 19 which is mounted for sliding movement in suitable guides formed on the pedestal 13. The rod 19 is caused to slide back and forth through its guides by a commercial double acting air cylinder 18. The movement of rod 19 back and forth causes the pins 27 to move back and forth in a straight line and at the same time the pin 33 and the ramming mechanism which it carries moves back and forth in a straight line. Other power means for propelling rod 19 and other than a straight line movement of pins 27 could be used if desired.

75 The air cylinder 18 is horizontally disposed so that its axis is in alignment with the rod 19 which in the construction shown is an extension of the cylinder piston rod. The cylinder 18 is secured to the pedestal 13. A piston (not shown) is secured to the piston rod of which rod 19 is an extension. The flow of air or other pressure fluid into cylinder 18 to actuate the piston and the rod 19 is controlled by a commercial four way valve 20 connected by pipes 21 to opposite 80 ends of the cylinder 18. A pipe 22 conducts the pressure fluid to the valve 20. Suitable commercial speed regulators 23 may be employed for regulating the speed of travel of the rod 19 back and forth. The valve 20 is 85 actuated by a swinging lever 24 which is located within convenient reach of the workman and is connected to the lever of the valve 20 by a rod 25.

90 To hold the rammer frame 34 and the ramming mechanism carried by it at right angles to its path of movement the second system of arms or links is arranged in the form of a parallel motion linkage constructed preferably as follows:—

An arm 37 is fixed to the fixed pivot 14 and at the outer end of this arm 37 a link 38 is pivotally connected. The opposite end of the link 38 is pivotally connected to one arm 39 of a bell crank lever which is rotatably mounted on the pivot pin 29 at the outer end of the arm 16. The arm 39 of the bell crank to which the link 38 is connected is of the same length as the arm 37. The link 38 is of the same length as arm 16. The other arm 40 of the bell crank lever is arranged at approximately right angles to the arm 39 and is pivotally connected at its outer end to a link 41 which is pivotally connected 100 at its opposite end to a pivot pin 42 fixed 105 to the rammer frame 34.

on the bracket 34 which carries the ramming mechanism. The arm 40 is of the same length and parallel to the center distance line between the pivot pins 33 and 42 on the bracket 34. The link 41 is of the same length as the arm 31. As the opposite links in each of the two four link chains just described are of equal length they will at all times maintain their parallelism, and the angular relation of the ramming mechanism bracket 34 to the fixed arm 37, and to the pedestal 13 which supports it, and also to the straight line path of travel of the pin 33 carrying the bracket 34 will remain constant. In the construction shown the bracket 34 is maintained at right angles to its path of travel.

The bracket 34 supporting the ramming mechanism is formed to provide hangers 43 which form bearings for a transverse two throw crank shaft 44. This crank shaft 44 is preferably rotated by an electric motor 45 mounted on the upper surface of bracket 34 and driving the crank shaft through a belt drive 46 or in any other suitable manner.

The mold rammers are arranged within a frame which is suspended from the bracket 34 and preferably comprises vertical corner bars 47, and suitably located longitudinal cross bars 48 and transverse bars 48^a, these bars being fastened together and to the bracket 34 in any suitable manner. Two guard plates or baffles 49 are fixed to the lower ends of the vertical corner bars and travel along the upper edges of the side walls of the flask 10 and serve to prevent the molding sand or material from being thrown sideways out of the flask during the ramming operation.

The two rammers are identical in construction and a description of one will apply to both. Each rammer is suspended from one of the cranks of the crank shaft 44 and includes a lower half bearing 50 having a depending tubular stem 51, an upper half bearing 52 bolted to the lower half bearing 50 forming the complete bearing of the rammer on the crankshaft 44. A tubular sleeve 53 is fixed on the stem 51 and at its lower end has an outwardly projecting annular flange 54 which supports a collar 55 having perforated lugs 56 through which tie bolts 57 fast to the ramming foot 58 may slide.

The ramming foot 58 is preferably of rectangular shape in plan view and is provided with an integral stem 59 on which is fixed in any suitable manner a tubular plunger 60. This plunger 60 slides in a wearing sleeve 61 fitting within the tubular casing sleeve 53. The wearing sleeve 61 has a plug 63 fixed inside its upper end. A spacing sleeve 64 is located inside of the tubular casing sleeve 53 and bears at its upper end against the end of the stem 51 and at its lower end against the sleeve 61 and the plug 63. The upward movement of the foot 58 relative to the cas-

ing sleeve 53 is cushioned by a helical compression spring 62 located in the plunger 60 and bearing at its lower end against the upper end of the stem 59 on the foot 58. This spring 62 bears at its upper end against the 70 plug 63 fixed in the wearing sleeve 61 and in this way holds the sleeve 61 in place. The downward movement of the foot 58 is limited by tie bolts 57 which are secured to the foot and slidably pass through lugs 56 on the retaining collar 55. A retaining nut and lock nut are provided at the upper ends of the bolts 57 and a resilient buffer 65 is interposed between the nuts and the lugs 56. The bolts 57 are preferably of uniform cross sectional area throughout their length so as to more adequately withstand the shock and strain to which they are subjected when the molding material is being rammed.

The shoe 66 is removably secured to the 80 under side of the foot 58 and preferably has a convex under surface to prevent the accumulation of packed molding material thereon. This shoe 66 may also be provided with downwardly projecting ribs 67 to provide for additional compressive action where required on the mold.

The lateral movement of each of the rammer feet 58 relative to the frame 34 and a vertical center line through the axis of the crankshaft 44 is yieldingly controlled in the 95 following manner:—

Transverse horizontal pivot pins 72 are fixed in oppositely located ears 73 on the foot 58. Approximately horizontal links 71 are pivotally connected at one end to the pins 72 and are pivotally connected at their 100 opposite ends to pins 72^a which are fixed at the lower ends of depending swinging bars 68. Two links 71 and two bars 68 are provided for each rammer foot 58. The bars 68 are pivoted at their upper ends on a transverse shaft 70 which is fixed at each end in the lower transverse bars 48 on the sides of the frame suspended from bracket 34. The bars 68 are limited in their swing by a bracket 74 within which they swing and which extends transversely across the rammer frame and is fast to opposite vertical corner bars 47.

The bars 68 are yieldingly held in a central position between the inner sides of the bracket 74 preferably in the following manner:—

Intermediate the ends of each pair of bars 68 is a cross rod 70^a extending from one bar to the other and fast in each. On this cross rod 70^a is pivotally mounted a horizontally disposed double ended plunger 75, the ends of the plunger extending outwardly through 120 slots in the bracket 74, located at opposite sides of the bracket and on each side of rod 70^a. On each plunger end a sliding sleeve 76 is mounted which sleeve has an annular flange at its outer end. The body of each 125

sleeve 76 slides freely in its slot in the bracket 74 and the flange on the sleeve forms a stop so that when the inner face of the flange is in contact with the outer surface of the bracket 74 the inner end of the sleeve 76 contacts with the side of the central boss 75^a on plunger 75 when the bars 68 are in the desired central position. Nuts 77 are provided at the outer ends of plungers 75 and interposed between these nuts 77 and the outer ends of the sleeves 76 are helical compression springs 78. The springs 76 act to move the sleeves into contact with the sides of the boss 75^a on the plunger 75 and thus 15 yieldingly hold the bars 68 in the desired central position.

The purpose of this construction just described is as follows:

Referring to Fig. 8, this diagram shows the relative positions of the lower end of the rammer foot 58 and the shoe 66, links 71 and crank of crankshaft 44 at several stages of one complete revolution of crankshaft 44, all in relation to a vertical center line through the crankshaft 44 and with the bars 68 which carry the pivots for the links in a central position. The upper circle represents the movement of the crank, the lower ellipsoid represents the movement of the shoe, the inclined vertical lines are center lines of the rammer case, plunger and shoe, and the inclined horizontal lines represent the center lines of the links 71. The several stages of one complete revolution of the crankshaft 36 are indicated by corresponding numerals. It is apparent that if the shoe 66 should be constrained to follow the ellipsoidal path shown in Fig. 8 at the time the rammer was moving across the mold, the shoe would drag the molding sand or material along with it in the direction of the travel of the rammer across the mold. To avoid this yieldingly held bars 68 allow the links 71 pivoted to them to move laterally in relation to the rammer frame and thus allow the rammer feet and the shoes fast to them to remain stationary in a lateral relation to the mold while the shoes are in contact with the molding sand or material, thus avoiding the lateral displacement of the sand or molding material relative to the mold.

Provision is made for levelling the top surface of the molding sand or material before the rammer shoes act to ram the material in the flask and also for removing the excess rammed sand or material from the top surface of the mold after the material has been rammed. The sand levelling and removing device comprises a transverse plate 79 which is located immediately ahead of the rammer feet 58 and which extends across the rammer frame from the guard plate 49 on one side of the frame to the other guard plate. This plate 79 is inclined upwardly 65 and outwardly from the rammer feet and

is fixed at each end to approximately horizontal swinging levers 80, which levers are pivotally mounted intermediate their ends on guard plates 49. The ends of levers 80 on the opposite side of their pivots from the plate 79 are provided with slidably adjustable counterweights 81. A handle 83 is attached to plate 79 for manipulation of the plate. The counter weights 81 are adjusted and set so as to balance the plate 79 with its handle 83 and levers 80. The upward and downward movement of the plate 79 away from and towards the mold is limited by adjustable stops 82 secured to an adjacent corner bar 47. Two stops 82 are provided, one being located so as to contact with the upper edge of one of the levers 80 and the other stop being located so as to contact with the lower edge of the same lever.

The operation of the machine is as follows:

At the time that the flask 10 is being placed on plate 11^a and also while molding sand or other material is being placed into the flask or mold, the ramming mechanism is in the position shown by the upper dotted lines in Fig. 1. During this time the operating lever is in the position shown by dotted lines in Fig. 4, and air or other pressure fluid has access to the outer end of cylinder 18, acting to hold the ramming mechanism in position, and the crankshaft 44 is rotating under power. The rammer feet are being moved up and down by the crank shaft and as they do not contact with the mold they follow the ellipsoidal path shown by diagram in Fig. 8. The link 68 is in its central position and the plate 79 may be at either the upper or lower limit or between the limits of its movement. After the sand or other molding material is in the flask or mold ready for ramming, the operator moves the lever 24 to the position shown by full lines in Fig. 4 thus admitting air to the inner end of the cylinder 18 and allowing the air to escape from the outer end, thereby causing the piston to move the rod 19 and traverse the ramming mechanism across the mold. The plate 79 contacts with the sand which is usually heaped above the top of the flask and since it is inclined during its forward movement it tends to ride over the sand, and being counterbalanced, is free to move upward until lever 80 contacts with upper stop 82.

This plate in its upper position during the forward movement of the rammer over the mold acts to level off the sand of the mold at any height above the flask as predetermined by the setting of upper stop 82. 125 As soon as the rammer feet come into contact with the sand of the mold and act to ram the sand, the feet being yieldingly controlled laterally in relation to the rammer frame by the bar 68 they are permitted by 130

the control to remain in a stationary position relative laterally to the mold while they are in contact with the mold material thus avoiding lateral displacement of the material in the mold.

When the ramming mechanism reaches the position shown by the full lines in Fig. 1, the operator moves the lever 24 from the position shown by full lines to the position shown by dotted lines in Fig. 4, thus causing the ramming mechanism to reverse its direction of travel and start to move backwards across the mold. Immediately after moving the lever 24 the operator depresses the handle 83 on the plate 79 until the lever 80 contacts with lower stop 82. The operator continues to depress the handle 83 until the lower edge of plate 79 contacts with the excess rammed sand on the upper surface of the mold. The weight of this excess sand against the inclined plate tends to hold the plate at the lower limit of its movement as predetermined by the setting of the lower stop 82. The ramming mechanism continues on its backward movement, ramming the mold and removing excess sand from the mold. When the piston of the cylinder 18 reaches the end of its stroke the travel of the ramming mechanism stops at the position shown by the upper dotted lines in Fig. 1. The rammer motor 45 and crank-shaft 44 rotate continuously.

It will be noted that the rotation of each of the pivotal points where friction occurs is small in amount, also that the movement of the driving members is much smaller than the movement of the driven parts at the other end of the pantograph. By this means the wear upon the friction surfaces is greatly reduced. The construction also permits of adequately protecting the bearings against the admission of grit and sand.

From the foregoing it is apparent that my invention provides a simple ramming mechanism for accomplishing the objects stated.

I claim as my invention:

1. A ramming machine comprising a main supporting arm, a second arm pivotally mounted on said main supporting arm, a pivotal support for said main supporting arm, means for moving said main supporting arm about its pivotal support, a ramming mechanism pivotally supported on said second arm, and means for moving said second arm to cause said ramming mechanism to follow a straight path across the element being rammed.

2. A ramming machine comprising a main supporting arm, an auxiliary arm pivotally mounted on said main arm, a pivotal support for said main arm, means for moving said main arm about its pivotal support, a ramming mechanism pivotally supported on

said auxiliary arm, and means actuated through motion derived from said main supporting arm for moving said auxiliary arm to cause said ramming mechanism to follow a straight path across the element being rammed.

3. A ramming machine comprising a series of horizontally swinging arms arranged in the form of a pantograph, a ramming mechanism supported at one extremity of said pantograph, and means for actuating said pantograph to cause said ramming mechanism to traverse the element being rammed.

4. A ramming machine comprising a main supporting arm, an auxiliary arm pivotally mounted on said main arm, a pivotal support for said main arm, a reciprocating driving member adjacent one end of said main arm, a driving link connecting said driving member and main arm, a ramming mechanism pivotally supported on said auxiliary arm, and a guide link connected at one end with said driving member and said drive link at their pivotal connection and at its other end with said auxiliary arm, said main arm, drive link, guide link and auxiliary arm forming a quadrangle in all positions of said main arm.

5. A ramming machine comprising a supporting arm, a pivotal support for said supporting arm, a ramming mechanism carried by said supporting arm, means for moving said arm about its pivotal support, means for moving said ramming mechanism relative to said arm to move it along a path across the element being rammed and means for holding said ramming mechanism in predetermined angular relations to said path.

6. A ramming machine comprising a main supporting arm, a pivotal support for said arm, an auxiliary arm pivotally mounted on said main supporting arm, a ramming mechanism pivotally mounted on said auxiliary arm, means for moving said main arm about its pivotal support, means for moving said auxiliary arm relative to said main supporting arm to cause said ramming mechanism to follow a predetermined path and means for moving said ramming mechanism about its pivotal support to hold said ramming mechanism in predetermined angular relations to said path.

7. A ramming machine comprising a main supporting arm, a pivotal support for said arm, an auxiliary arm pivotally mounted on said main supporting arm, a ramming mechanism pivotally mounted on said auxiliary arm, means for moving said main arm about its pivotal support, means for moving said auxiliary arm about its pivotal support to cause said ramming mechanism to follow a straight path across the element being rammed, and parallel link means for moving said ramming mechanism about its pivotal

support to hold said ramming mechanism in predetermined angular relations to said path.

8. A ramming machine comprising a main supporting arm, a pivotal support for said main arm, an auxiliary arm pivotally mounted on said main arm, a ramming mechanism pivotally mounted on said auxiliary arm, means for moving said main supporting arm about its pivotal support, means for moving said auxiliary arm about its pivotal support to cause said ramming mechanism to follow a straight path across the element being rammed, a bell crank lever movably mounted on the pivot supporting said auxiliary arm and said main arm, a guide link arranged parallel with said main supporting arm and pivotally connected at opposite ends with one arm of said bell crank lever and a stationary portion adjacent the pivotal support for said main arm and a second guide link arranged parallel with said auxiliary arm and pivotally connected at opposite ends with the other arm of said bell crank lever and said ramming mechanism whereby upon moving said main arm said ramming mechanism is moved along a straight path and is maintained in the same relative position thereto.

9. A ramming machine comprising a series of horizontally swinging arms arranged in the form of a pantograph, a ramming mechanism pivotally supported at one extremity of said pantograph to cause said ramming mechanism to traverse the element being rammed, and means for moving said ramming mechanism about its pivotal support to hold said ramming mechanism in predetermined angular relations to its path of movement.

10. A ramming machine comprising a frame, means for moving said frame across the element being rammed, a crank shaft journaled in said frame, means for operating said crank shaft, a depending ramming member secured to said crank shaft and reciprocated thereby, a ramming foot at the lower end of said ramming member, a horizontal guiding member pivotally secured at one end to said ramming member at the lower end thereof and spring means mounted on said frame and cooperating with said horizontal guiding member to yieldingly hold said rammer foot in a central position below said crank shaft, and permit of lateral movement thereof relative to said frame when said frame is moved and said foot is in contact with the element being rammed.

11. A ramming machine comprising a frame, means for moving said frame horizontally across the element being rammed, a crank shaft journaled in said frame, means for operating said crank shaft, a depending ramming member secured to said crank shaft

and reciprocated thereby, a ramming foot at 65 the lower end of said ramming member, a horizontal link pivotally secured at one end to said ramming member at the lower end thereof, a lever pivotally secured at one end to the opposite end of said link and at its 70 other end to said frame, and spring means mounted on said frame and cooperating with said lever to yieldingly hold said rammer foot in a central position below said crank shaft, and permit lateral movement thereof 75 relative to said frame when said frame is moved and said rammer foot is in contact with the element being rammed.

12. A ramming machine comprising a frame, means for moving said frame horizontally across the element being rammed, a crank shaft journaled in said frame, means for operating said crank shaft, a depending rammer secured to said crank shaft and reciprocated thereby, a horizontal link pivotally secured at one end to said rammer at the lower end thereof, a vertical lever pivotally secured at its lower end to the other end of said link and at its upper end to said frame, a bracket carried by said frame, and opposed springs carried by said bracket and yieldingly holding said lever in a central position, and permitting lateral movement thereof relative to said frame, when said frame is moved and said rammer is in contact with the element being rammed.

13. A ramming machine comprising a frame, means for moving said frame horizontally across the element being rammed, a crank shaft journaled in said frame, means 100 for operating said crank shaft, a depending rammer secured to said crank shaft and reciprocated thereby, a ramming foot yieldingly secured to the lower end of said rammer, a horizontal link pivotally secured 105 at one end to said rammer foot, a vertical lever pivotally secured at its lower end to the other end of said link and at its upper end to said frame, a bracket carried by said frame, and opposed springs carried by said 110 bracket and yieldingly holding said lever in a central position, and permitting lateral movement of said foot relative to said frame, link and levers when said frame is moved and said ramming foot is in contact with the 115 element being rammed.

14. A ramming machine comprising a frame, means for moving said frame horizontally across the element being rammed, a crank shaft carried by said frame, means 120 for rotating said crank shaft, a depending rammer secured to said crank shaft and reciprocated thereby, a ramming foot yieldingly secured to the lower end of said rammer, and means for yieldingly holding said 125 rammer in a central position, and permitting lateral movement of said foot relative to said frame when said frame is moving

- and said foot is in contact with the element being rammed, comprising a shaft secured to said frame, a pair of depending levers pivotally secured at their upper ends to said shaft, a horizontal rod connecting said levers intermediate their ends, a pair of horizontal links pivotally connecting the lower ends of said levers with said foot, a bracket embracing said levers adjacent said rod and provided on its opposite sides with slots, sliding sleeves arranged in each of said slots and each provided with a head limiting its inward movement, a horizontal double ended plunger secured to said rod and extending outwardly through said sleeves, nuts provided at the opposite ends of said plunger and a compression spring interposed between each of said nuts and the corresponding head of said sleeve.
15. In a ramming machine a frame, a crank shaft journaled in said frame, means for operating said crank shaft, and a rammer carried by said crank shaft and reciprocated thereby, said rammer comprising a bearing member secured to said crank shaft, a sleeve secured to said bearing member, a flange at the lower end of said sleeve, a bracket supported by said flange, a ramming shoe below said bracket, sliding bolts limiting the downward movement of said shoe relative to said bracket, a plunger projecting upwardly from said shoe within said sleeve, a compression spring within said plunger and sleeve and yieldingly holding said shoe in a downwardly extended position, and spacing elements arranged within said sleeve and interposed between the upper end of said spring and said bearing element.
20. 16. In a ramming machine, a frame, a ramming mechanism carried by said frame, means for moving said frame horizontally over the surface of the sand to be rammed,

an inclined plate pivotally mounted on said frame and adapted when moved in one direction to level the surface of the sand, and in the opposite direction to engage and scrape the surface of the sand and be held in a depressed position thereby and means for adjustably limiting the upward and downward movement of said plate.

17. In a ramming machine a frame, a ramming mechanism carried by said frame, means for moving said frame horizontally over the surface to be rammed, a pair of arms pivotally secured to opposite sides of said frame, a plate carried at the ends of said arms, said plate being inclined whereby upon moving said frame in one direction its underface engages the surface of the sand to level the same and upon moving said frame in the opposite direction said plate is depressible to engage its edge with the sand and elevate the surplus sand therefrom, and adjustable stops for limiting the upward and downward movement of said plate.

18. In a ramming machine, a frame, a crank shaft journaled in said frame, means for operating said crank shaft, and a rammer carried by said crank shaft and reciprocated thereby, said rammer comprising a bearing member secured to said crank shaft, a sleeve secured to said bearing member, a flange at the lower end of said sleeve, a bracket supported by said flange, a ramming shoe below said bracket, sliding bolts limiting the downward movement of said shoe relative to said bracket, a plunger projecting upwardly from said shoe within said sleeve and a compression spring within said plunger and sleeve and yieldingly holding said shoe in a downwardly extended position.

In testimony whereof I hereby affix my signature.

SHERWOOD C. BLISS.
